PHONOGRAPH MECHANISM

Russell H. Rich, Elyria, Ohio, assignor to The
General Industries Company, Elyria, Ohio, a
corporation of Ohio

Application December 18, 1937, Serial No. 180,542

8 Claims. (CL 274—39)

This invention relates to phonograph mechanisms, and relates more particularly to means associated with the turntable support adapted to retard vibration transmitted from the driving mechanism therefor.

It has heretofore been proposed to provide a support for a phonograph turntable formed of cushioning material such as rubber and wherein the turntable hub rests upon a horizontally extending flange of the support and a short vertically extending sleeve portion of the support is disposed intermediate the driving shaft and the turntable hub for a short distance, this construction being illustrated in a United States patent to Schmittgen, No. 1,979,350, issued November 6, 1934.

I have devised a support for phonograph turntables wherein a rubber or the like cushioning element comprises a portion encasing the upper end of the drive shaft and insulating the drive shaft against electrical shock to a person operating the phonograph and a vertically extending portion encircling the drive shaft substantially throughout the extent of the turntable hub providing a considerable area for damping vibrations tending to be transmitted from the drive shaft to the turntable and supported record.

Additionally, the contact of the support element and turntable hub substantially throughout the hub extent increases the frictional driving contact therebetween.

It is an object of my invention therefore to provide an improved support means for a phonograph turntable which will minimize the transmission of vibration from the driving mechanism to the turntable and a record supported thereby.

Another object of my invention is to provide an improved support for phonograph turntables which will insulate the drive shaft against the transmission of electrical shock to an operator.

Another object of my invention is to provide improved support means for phonograph turntables which will prevent the distortion of the sound record supported on the turntable through the transmission of vibrations from the driving mechanism.

Another object of my invention is to provide in connection with the turntable shaft of a phonograph or like mechanism, means for absorbing variation in driving torque and vibration.

Other objects of my invention and the invention itself will become increasingly apparent from

consideration of the following description and drawing in which:

Fig. 1 is a cross-sectional view, illustrating in simplified form a phonograph mechanism, including the turntable, drive shaft, and support embodying my invention;

Fig. 2 is a cross-sectional view to an enlarged scale of the support of Fig. 1, and

Fig. 3 is a section taken along line 3—3 of Fig. 1.

Referring now to the drawing, I have indicated generally at 10 a housing within which is contained a driving motor and transmission gears for driving a vertical turntable shaft 12, illustrated as projecting upwardly out of the housing 10.

The shaft 12 is illustrated as comprising a lower tapered portion and an upper cylindrical portion but the shaft may be cylindrical throughout its extent if desired.

A pin 13 extends diametrically through the shaft above the housing. A metal clutch device or washer 14 rests upon the pin 13, the perforation of the washer being larger than the shaft 12, and the washer at diametrically opposite portions thereof where it rests upon the pin 13 is provided with cooperating pairs of downwardly projecting lugs 15—15 on opposite sides of the pin 13. Thus the lugs provide two notches which embrace opposite end portions of the pin 13. The lugs 15 are preferably pressed out of the metal of the main body portion of the washer 14, as best illustrated in Fig. 3.

The construction so far described constitutes no essential part of my invention and any well known form of driving mechanism may be employed.

I have generally indicated at 16 a support element formed of rubber or the like cushioning material and which, when employed with electrically operable phonographs, is formed of material having suitable electrical insulating qualities. The element 16 preferably comprises a central generally tubular portion 17, a radially outwardly extending flange 18, an inverted cup or cap portion 19. When the shaft 12 is provided with a shoulder as shown in Figs. 1 and 2 herein, the internal walls of the element 16 are offset to provide a shoulder 20 abutting said shoulder on the shaft 12. The turntable in the form illustrated herein comprises a horizontal body portion 22 at the center of which is a downwardly extending hub 23. The turntable may be covered with felt or like material and the upper end of the shaft 12 may project upwardly through a perforation in the felt and the phonograph rec-

ord may be centered on the upper end of shaft 12 in the usual way. The tubular portion 17 is substantially co-extensive with the turntable hub 23 and the external walls of this portion are preferably tapered to insure a tight engagement with the inner walls of the turntable hub although I contemplate that the external walls of portion 17 may be cylindrical, if desired. The internal diameter of the cap portion 19 substantially corresponds to the outer diameter of the shaft 12 to insure a gripping engagement therebetween whereby the support element may be rotated by the shaft. The inner walls of the hub portion 23 may be progressively increased in diameter or of 15 cylindrical form, dependent on the shape of shaft 12 and the element 16.

The flange 18 of the support element in the form illustrated overlies a washer 14 which is preferably of approximately the same diameter 20 as said flange and the frictional contact therebetween, together with the gripping engagement of the cap portion 19 and the tubular portion 17 with the drive shaft 12, effects the driving engagement between the shaft and the support element. Any vibration transmitted by the driving mechanism to the drive shaft will tend to be transmitted from the drive shaft to the turntable through the support element. However, due to the fact that the tubular portion of the element 30 16 is interposed between shaft 12 and portion 23 of the turntable, such vibration is damped or materially reduced so that vibrations of the motor are absorbed in the cushion element or support 16 instead of being transmitted through 35 shaft 12 to the turntable. As the washer 14 has the bore therethrough spaced from the shaft and since the pin 13 may move relative to the washer 16, any tendency to transmit vibration to the washer is minimized.

40 It is to be understood that I contemplate the use of a support element without the flange 18 having only a shaft encasing tubular portion 17 and a cap portion 19 and that such an embodiment is within the spirit of my invention, but 45 preferably the flange 18 is employed to cushion and electrically insulate the entire turntable from the shaft.

It should also be noted that the portion of the drive shaft which might ordinarily be touched 50 by a person placing a record on the turntable or when operating the phonograph, being covered by the inverted cap of electrically insulated material, in event of current being transmitted to the shaft due to a "short" in the circuit, there 55 will be no danger of transmitting electrical shock to an operator.

Although I have shown and described a preferred form of my invention, I contemplate that 60 numerous and extensive departures may be made therefrom without departing from the spirit of my invention and the scope of the appended claims.

I claim:

1. The combination with a vertically disposed 65 driving shaft of a phonograph and a turntable having a downwardly projecting hub, of a support on the shaft for the turntable, a cushioning support element having a radial flange abutting and frictionally supporting the turntable 70 hub, the support element including a generally tubular portion having its outer walls engageable with the inner walls of the hub, and an inverted cup portion shrouding the shaft upper end, said cup portion formed integral with the 75 tubular portion.

2. The combination with a vertically disposed driving shaft of a phonograph mechanism and a turntable having a downwardly projecting hub, of a supporting washer rotatably mounted on the shaft, a support element formed of cushioning material adapted to damp vibrations comprising a flange abutting the washer and frictionally supporting the hub, a generally tubular portion having its inner walls conforming to the shape of the shaft and its outer walls engaging the hub inner walls substantially throughout the extent of the hub walls, and the tubular portion terminating in a cap portion encasing the upper end of the shaft and providing an electrical insulating cover for said shaft end. 15

3. The combination with a driving shaft of a phonograph mechanism and a turntable having a downwardly projecting hub, of cushioning means on the shaft for the turntable comprising a generally tubular portion telescoped over said shaft and disposed between said shaft and said downwardly disposed hub portion for a considerable portion of its length, and having a cap portion formed of electrical insulating material projected over the upper end of the shaft and enclosing the same and a lower flange portion adapted to substantially underlie the lower end of said hub. 20

4. The combination with a vertically disposed driving shaft of a phonograph mechanism and a turntable having a downwardly projecting hub, of a support on the shaft for the turntable, of a washer rotatably supported by the shaft, a cushioning element having a flange portion abutting the washer frictionally supporting the turntable hub and a vertical extending portion having a closed end grippingly engaging the shaft. 35

5. The combination with a vertically disposed driving shaft of a phonograph mechanism and a turntable having a downwardly projecting hub, of a support on the shaft for the turntable, of a washer rotatably supported by the shaft, a cushioning element having a flange portion abutting the washer frictionally supporting the turntable hub and a vertical extending portion grippingly engaging the shaft and enclosing the upper end portion. 40

6. A phonograph turntable support element adapted to be interposed between a vertically disposed driving shaft having a supporting element rotatable therewith and a turntable having a downwardly projecting hub, said support element being formed of cushioning material having electrical insulating properties and comprising a portion of inverted cup form for telescopingly 50 and tightly engaging the shaft, and a radial flange extending from the lower portion of the support element for disposition between the supporting element and the lower face of the hub, to electrically insulate the tip portion of the shaft 55 and cushion the turntable from the shaft.

7. In a phonograph, the combination of a motor including a spindle, a turntable having a hub provided with a bore, and means coupling said hub to said spindle to effect driving engagement 65 therebetween, said means including a soft rubber sleeve surrounding said spindle and received within said bore characterized in that said spindle protrudes above said turntable whereby to threaded receive a record, and characterized 70 further in that said rubber sleeve completely encases said spindle whereby the protruding end of said spindle is vibration insulated from the record.

8. In a phonograph, the combination of a mo- 75

tor including a spindle, a turntable having a hub provided with a bore, and means coupling said hub to said spindle to effect driving engagement therebetween, said means including a soft rubber sleeve surrounding said spindle and received within said bore characterized in that said spindle is substantially conical along a portion of its length and terminates in a substantially cylindrical portion at its upper extremity, characterized further in that said bore is also substantially

conical and said conical spindle portion fits within said bore, said cylindrical portion protruding above said turntable whereby to threadedly receive a record, and characterized still further in that said rubber sleeve completely encases said spindle whereby said cylindrical spindle portion is vibration insulated from the record and said conical spindle portion is vibration insulated from said turntable. 5
